UNITED STATES PATENT OFFICE.

JOHN J. McGUIRE, OF NEW YORK, N. Y.

DUMPING-WAGON.

1,133,301.

Specification of Letters Patent. Patented Mar. 30, 1915.

Application filed May 10, 1913. Serial No. 766,747.

To all whom it may concern:

Be it known that I, JOHN J. McGUIRE, a citizen of the United States, and a resident of the city of New York, borough of 5 Manhattan, in the county and State of New York, have invented a new and Improved Dumping-Wagon, of which the following is a full, clear, and exact description.

This invention relates to improvements 10 in dumping wagons, and has for an object to provide an improved structure which may be readily dumped and again readily restored to its original position.

Another object of the invention is to provide in a dumping wagon means for automatically removing the end or tail-board as the wagon is dumped.

A still further object of the invention is to provide a gearing mechanism associated 20 with the wagon body and with the frame or running gear, which may be operated in one direction for moving the wagon body to a dumping position and operated in an opposite direction for moving the wagon 25 from a substantially dumped position back to its original position on the frame or running gear.

In carrying out the objects of the invention, a running gear is provided formed with 30 a supporting frame. On this supporting frame is arranged a plurality of rollers designed to support a body which may be dumped. This body is adapted to be actuated by a rack pivotally connected therewith, which in turn is moved by suitable gearing, the gearing being arranged with crank engaging members which when operated in opposite directions will move the rack and wagon body in opposite directions, namely, to a dumped position and 40 from the dumped position to the original working position. Connected with the wagon body and the frame is an arrangement of levers connected with the tail-board of the wagon body so as to automatically raise the tail-board simultaneously with the dumping of the body.

A practical embodiment of the invention is represented in the accompanying drawings forming a part of this specification, in which similar characters of reference indicate corresponding parts in all the views.

Figure 1 is a side view of an embodiment of the invention; Fig. 2 is a side view 50 on an enlarged scale of a wagon embodying the invention; Fig. 3 is a top plan view

of the wagon frame and running gear shown in Fig. 2; Fig. 4 is a side view of the structure shown in Fig. 3, the rear axle and bracing links being removed; Fig. 5 is an enlarged detail fragmentary sectional view disclosing the body moving rack and the gearing therefor; and Fig. 6 is an enlarged detail fragmentary side view of one of the rear supporting springs and the links associated therewith and with the rear axle.

Referring to the accompanying drawings by numerals, 1 indicates an automobile structure provided with suitable steering apparatus, engines, and the like. The engine and driving mechanism of the automobile structure is designed to drive one or more chains 2 which engage suitable sprockets 3 arranged on the front axle 4 of the dumping wagon 5. The traction 75 wheels mounted on axle 4 are connected therewith so as to act as drivers in the usual manner. In order to provide a proper steering of the device, axle 4 is designed to contact with a suitable turntable or fifth wheel 80 6, supporting the front part of the dumping wagon. The rear axle 7 of the dumping wagon 5 is provided with any kind of traction wheels 8. Mounted on the turntable 6 are a plurality of longitudinally arranged beams 9 which, together with the front beam 9' and any desired number of auxiliary cross beams, forms a frame. The rear end of each of the beams 9 carries a bracket 10 (Fig. 6) which accommodates 85 pins 11 and 12. The pins 11 and 12 act as journal pins for links 13 and 14, which in turn are pivotally connected by pins 15 and 16 with a suitable clamp 17 held in place by bolts, or otherwise on axle 7. The clamp 17 is formed with squared portions to properly fit the squared shaft 7, but it will be perfectly evident that if shaft 7 was of any shape the clamp could be made of a corresponding shape. A spring 18 has one 95 end arranged to pivotally engage the journal pin 12 on bracket 10, while the opposite end loosely presses against axle 7. The center of the spring is clamped to the beam 9 by suitable substantially U-shaped clamps 105 19 and cross bars 20. Nuts of any desired kind are provided for members 19 so as to firmly clamp bars 20 against the spring which presses against the filling block 21, and block 21 in turn rests against plate 22 110 which carries the brackets 10. Plate 22 is connected in any desired way with the

beam 9. In this way a resilient support is provided for the rear of the wagon 5, while any usual or preferred form of spring may be used with the turntable 6 at the forward 5 part of the wagon. The arrangement of the links 13 and 14 co-acts with the brackets 10 and clamp 17 and with the spring, so that when the rear of the wagon is moved up and down, the axle 7 will be normally held 10 in proper position and prevented from turning.

Arranged on each of the beams 9 are a plurality of brackets 23 carrying rollers 24 which act as antifriction supporting means 15 for the body supporting beams 25 forming part of the body 26. The body supporting means 25 are designed to freely slide to the rear and thus allow the wagon to dump, as shown in Fig. 2, whenever desired. Rigidly 20 connected with the two side beams 25 are stops or hook members 27, designed to engage projections 28 and 29 arranged on the beams 9. The projections 28 and 29 are merely the ends of bar 30 extending beyond 25 the side beams 9, as clearly shown in Fig. 3. If desired, a central hook, or a number 30 of central hooks, could be used without departing from the spirit of the invention, as the same easily operate and correctly engage the bar 30.

In order that the body 26 may be moved back and forth as desired even when there is a load thereon, a rack 31 is pivoted at 32 to a suitable bracket 33 mounted on the body 26. Preferably there are two of these racks 31, as shown in Fig. 3, so as to cause a more even movement of the body 26. The racks 31 are designed to engage a pinion 34 rigidly secured to shaft 35. The shaft 35 has 40 also rigidly secured thereto gears 36 near each end designed to mesh with gears 37 and 38, and gears 39 and 40, respectively. The gears 37 and 39 are rigidly secured to the shaft 41, while gears 38 and 40 are rigidly secured to shaft 42. Shafts 41 and 42 extend beyond the outside beam 9 on each side of the wagon so as to receive clutch heads 43. The clutch head 43 on shaft 42 is designed to rotate shaft 42 in one direction when a crank 44 is applied thereto so as to cause the body 26 to move back from a dumped position to a position shown in full lines in Fig. 2. When it is desired to cause the body 26 to dump, crank 44 is moved over to either of the clutch heads 43 on shaft 41 and rotated. After the wagon body 26 has been moved back to its working position, as shown in Fig. 2, a locking pin 45 may be used and may be passed through 50 a projection 46 at the forward end of the body 26 and through a suitable bracket 47 (Fig. 2). In addition to these securing means suitable hooks 48 may be used. The hooks 48 are pivotally connected with any 55 part of the running gear, as for instance

cross beam 9', and are designed to engage suitable pins arranged on the wagon body 26. In moving the wagon body 5 from the dumped position back to the working position, the forward end is designed to be 70 stopped by the cross beam 10 and also by suitable stops 49 associated with the cross beam 10.

In order that the end board or tail-board 50 shall automatically open or be removed, 75 the same is pivotally connected at 51 to an arm 52 on each side of the wagon. The arms 52 are pivotally connected at 53 to the wagon and have pivotally connected intermediate their length links 54. Pivotally 80 connected with the links 54 are connecting rods 55, in turn pivotally connected at 56 to the outside beams 9. In order to hold the tail-board 50 properly in position at the lower end, a hook 57 may be used which, 85 of course, is to be unfastened previous to the dumping of the wagon. As the body 26 moves to the rear the links 54 and rod 55 gradually assume the position shown in dotted lines in Fig. 2, but do not act upon 90 the tail-board 50 until they have formed a straight line, whereupon they will prevent any further bodily rearward movement of the arms 52 that will hold the upper part 95 against further movement, and as the lower part continues to move the result will be that the tail-board will be raised as shown in dotted lines in Fig. 2. In order that this action may be carried out without undue friction, anti-friction rollers 58 may be arranged at the rear of the wagon body 26 for guiding the tail-board 50 in its movement. When the wagon body 26 is moved back to its original position the tail-board will automatically move to its correct position so 100 that the hook 57 may be again placed in position manually.

Having thus described my invention I claim as new and desire to secure by Letters Patent:—

In a dumping wagon of the class described, a running gear provided with a supporting frame, a body adapted to be dumped therefrom, said body being formed with a tail board, a pair of arms pivotally connected at one end with said body and at the other end with the upper edge of said tail board, means for locking the lower end of said tail board in place while said body is on said frame, a link pivotally connected to each of said arms substantially central thereof and extending normal thereto when the body is on said frame, a rod pivotally connected to each of said links and to said supporting frame, said rods being connected with said supporting frame in front of said arms, whereby when said body is dumped the tail board and the upper end of said arms will move therewith until said links and said rods move to a 130

position substantially in alinement, where-
upon a further swinging movement of the
arms will be stopped, while said body con-
tinues its movement until it strikes the
5 ground, thus causing a separation of the
tail board and the body.

In testimony whereof I have signed my

name to this specification in the presence of
two subscribing witnesses.

JOHN J. McGUIRE.
